ATTORNEY

UNITED STATES PATENT OFFICE

HARRY STEIN, OF PHILADELPHIA, PENNSYLVANIA

GLARE PREVENTER

Application filed March 1, 1930. Serial No. 432,351.

This invention relates to glare preventers for vehicles and has for an object to provide a plate of any sub-transparent glare reducing material with improved means for mounting the same relative to the vehicle structure.

A further object of the invention is to provide brackets mounted rigidly upon the vehicle structure with a frame carried by the brackets and oscillatable relative thereto from operative to inoperative position with a glare reducing plate slidably mounted upon said frame.

A further object of the invention is to provide a frame with proper mountings therefor, a sub-transparent glare reducing plate mounted to slide relative to the frame, and means for frictionally holding the plate for manual action.

With these and other objects in view, the invention comprises certain novel parts, elements, units, constructions, mechanical movements and functions as disclosed in the drawings, together with mechanical and functional equivalents thereof, as will be hereinafter more fully described and claimed.

In the drawings:

Figure 1 is a view of the improved glare preventer shown in full lines in end elevation, in dotted lines in lowered position, and in broken lines in inoperative position,

Figure 2 is a view of the device in front elevation,

Figure 3 is a longitudinal transverse sectional view taken on line 3-3 of Figure 2,

Figure 4 is an enlarged detailed view with parts of the bracket broken away,

Figure 5 is an enlarged detailed view of the means for holding the sliding plate relative to the frame, and

Figure 6 is an enlarged detailed sectional view taken on line 6-6 of Figure 2.

Like characters of reference indicate corresponding parts throughout the several views.

The improved glare preventer which forms the subject matter of this application, comprises a frame 10 constructed of channel material or the like, as shown more particularly at Figure 6. This frame 10 is provided

intermediate its upper and lower edges with pintles 11 journaled in brackets 12, which said brackets are secured to any convenient or appropriate part of a vehicle structure, as for instance, the roof of the body, conventionally shown at 13.

The brackets 12 are provided each with a socket 14 in which a spring 15 is mounted surrounding the pintles 11 with a cap nut 16 in threaded connection with the pintles. This cap nut 16 is provided upon one side with a rosette construction coacting with a complementary rosette construction upon the bracket 12 so that as the frame 10 is oscillated, carrying therewith the pintle 11, the nut 16 will yield by reason of the spring action and the rosette construction will hold the frame at any manually secured position, wear plates 17 being provided between the bracket 12 and the frame 10.

The frame 10 is also provided with a cut-out part 18 upon each end forming shoulders 19 and 20.

Slidably mounted within the channel construction of the frame 10 is a plate of sub-transparent glare reducing material 21. This material may be, as conventionally indicated, of glass of such consistency or coloring as to reduce the glare, or it may be of any of the usual perforated or grilled structures in common use, and the invention is in no way limited to the particular material of the plate, or the manner of fabricating, so that visibility is provided by less than complete transparency and of a nature to reduce glare.

The plate 20, if of glass or any similar material, is provided with a containing frame 22 preferably, though not necessarily, continuing entirely around said plate 21 and provided with any convenient means for manual engagement, as the handle 23.

The frame 18 is so proportioned and contoured as to slide easily within the frame 10 and lugs 24 are carried by the frame 22 so positioned as to engage at its upper limit of movement, as shown at 20, and at its downward movement, as shown at 19, so that the plate 21 may be raised and lowered manually.

To provide for holding the plate 21 and its frame 22 at such manual adjustment, the end margin at one or both ends of the frame 22 are provided with indentations 25 with a stop 26 here shown as of the ball type, spring pressed, but the spring 27 normally holds the plate and frame against accidental movement, while yielding to manual stress.

The spring and ball are preferably contained in an offset 28 and in the drawings this offset, shown at both ends of the drawings, indicates the use of the stop at both ends of the plate, it being understood, however, that this will not limit the invention and that either or both ends may be employed, as found necessary.

When out of operation the plate occupies a position shown in broken lines in Figure 1, that is to say, swung up into proximity to the top of the vehicle, and is held in such position by the spring pressed rosette.

When the device is to be used, it is simply manually oscillated upon the pintles 12 to vertical or substantially vertical position, and the plate of glare reducing material is adjusted to the proper height required by the driver by simply sliding the plate up or down in the channeled frame 10.

The invention is hereby claimed as follows:

1. A glare preventer comprising a frame of channel material open at one side, a second frame of channel material enclosing a subtransparent sheet, said second frame mounted to slide wholly within and partly without the first frame, said first frame having a cut out in one margin forming limiting stops, and a lug carried by the second frame cooperatively engaging said stops.
  2. A glare preventer comprising a frame of channel material open at one side, means pivoting said frame to swing, a second frame of channel material enclosing a subtransparent sheet, said second frame mounted to slide wholly within and partly without the first frame, said first frame having a cut out in one margin forming limiting stops, and a lug carried by the second frame cooperatively engaging said stops.
- 50 In testimony whereof I have signed my name to this specification.

HARRY STEIN.
